(57) **CLAIM**

The ornamental design for an earphone case, as shown and described.

DESCRIPTION

FIG. 1 is a front elevational perspective view showing the new design for an earphone case;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The surface contour lines in the drawings illustrates the contour of the claimed design and not a claimed surface pattern, edge(s) or seam(s) (i.e., are not claimed ornamental feature(s), but rather contour lines).

1 Claim, 7 Drawing Sheets
